UNITED STATES PATENT OFFICE.

FREDERICK A. BLACHLY, OF COUNCIL BLUFFS, IOWA.

CYLINDER BORING AND GRINDING MACHINE.

1,252,994.

Specification of Letters Patent.

Patented Jan. 8, 1918.

Application filed June 18, 1917. Serial No. 175,426.

To all whom it may concern:

Be it known that I, FREDERICK A. BLACHLY, a citizen of the United States, residing at Council Bluffs, in the county of Pottawattamie and State of Iowa, have invented certain new and useful Improvements in Cylinder Boring and Grinding Machines; and I do declare the following to be a full, clear, and exact description of the invention, such 10 as will enable others skilled in the art, to which it appertains to make and use the same.

My invention has for its object to provide a simply constructed yet highly efficient and 15 durable means for boring and grinding the cylinders of internal combustion engines and the like, the present embodiment of the device being so constructed as to render it applicable to numerous types of lathes al- 20 though it will be obvious that the machine could well be built completely to operate independently of parts of any other machines.

With the foregoing general object in view, the invention resides in certain novel fea- 25 tures of construction and unique combinations of parts to be hereinafter fully described and claimed, the descriptive matter being supplemented by the accompanying drawings which constitute a part of this ap- 30 plication, and in which:

Figure 1 is a perspective view of the im- proved machine;

Fig. 2 is a longitudinal section through the boring and grinding mechanism showing 35 the tool carrying shaft in its neutral position and illustrating a grinding wheel on said shaft.

Fig. 3 is a view similar to Fig. 2 but illustrating the tool carrying shaft adjusted for 40 operation, locked against rotation and equipped with a boring tool;

Fig. 4 is a horizontal section on the plane of the line 4-4 of Fig. 2; and

Figs. 5 and 6 are perspective views of the 45 opposite ends of the hollow shaft through which the tool carrying shaft extends.

In the drawings above briefly described the numeral 1 has reference to a bed which will in most cases be the bed of an ordinary 50 lathe and will include the usual tracks 2 upon which a carriage 3 is mounted for manual adjustment by means of the hand wheel 4 and for mechanical movement by way of the screw 5 which latter is driven in the 55 usual or any preferred manner.

The carriage 3 is provided with a trans-

verse dovetail rib received in a dovetail groove 6 in the under side of a rectangular base plate or auxiliary carriage 7 which may thus slide transversely of the tracks 2. For 60 shifting the carriage 7 in this manner, a feed screw 8 is rotatably mounted in a bearing 9 on said carriage and is threaded through a fixed nut 10 on the carriage 3. A rectangular rib 11 is formed longitudinally of the 65 carriage 7 and is provided with a common type of inverted T-shaped slot 12 in which bolts 13 slide for securing a pair of work holding brackets 14 in adjusted position on the carriage 7. The bases of the brackets 14 are formed with notches 15 receiving the rib 11 whereby they are guided in their movement, and work supporting plates 16 contact with the upright front edges of said brackets and may be adjusted vertically by means 70 of the screws 17 which are passed through ears 18 on the upper ends of the brackets. Bolts 19 are provided for clamping the plates 16 after they are once adjusted, and said plates are provided with suitable slots 80 20 by means of which an engine cylinder or the like may be bolted thereto in position for boring or grinding.

A pair of arched bearing supports 21 are mounted on one end of the bed 1 and are 85 provided at their crowns with aligned bearings 22 rotatably receiving a rotary member in the form of a hollow shaft 23 which extends longitudinally of the machine and is held against longitudinal shifting by any 90 preferred means, such as collars. A comparatively large gear 24 is secured on the shaft 23 and meshes with a pinion 25 on a short longitudinal shaft 26 carried by the supports 21 and driven from the screw 5 95 by any suitable means such as the pulleys 27 and belt 28. By this arrangement, the shaft 23 is slowly rotated and at the same time the carriage 3 will be fed slowly toward the boring or grinding tool being used.

For carrying the aforesaid tool, a shaft 29 extends through the hollow shaft 23 and is rotatably received at its ends in suitable bearings 30 and 31 preferably of the ball- or roller type. The shaft 29 is preferably reduced at its points of passage through the bearings 30 and 31 to form thrust preventing shoulders 29^a. The bearings 30 and 31 are carried on the ends of a tubular sleeve 32 which extends through the shaft 23 and said bearing 30 is provided with outwardly projecting flanges 30^a mounted pivotally in

ears 33 which project from one end of the shaft 23.

The sleeve 32, near the end thereof having the bearing 31, is provided with a 5 clamping collar 34 having trunnions 34^a received in ears 35^a on a carriage plate or slide 35, the latter being mounted slidably on a 10 guide rib 36 formed across one end of the shaft 23. A screw or the like 37 is provided for adjusting said slide along the track as seen more particularly in Fig. 2. By this arrangement, the tool carrying shaft 29 may be angled with respect to shaft 23 after insertion of the tool in the engine cylinder and thus said tool may be properly 15 adjusted for operating upon the interior of said cylinder.

Either a boring head 38 carrying a boring tool 39 or a grinding wheel 40 may be secured on the front end of the shaft 29 according to the work to be done. If the boring tool is to be used, the shaft 29 must be held against rotation after proper adjustment of its front end so that the slow turning of the shaft 23 will move the tool 39 around a circular course to bore the cylinder, and for so locking said shaft I provide the head 38 with a set screw 41 for clamping it to the bearing 31 of the fixed 20 sleeve 32 as indicated in Fig. 3. Other means, however, may be employed for this purpose.

After boring of the cylinder the grinding wheel 40 is substituted for the head 38 and 35 by means of a belt 42 and countershaft 43, the tool carrying shaft 29 is rapidly rotated, said shaft 29 having been adjusted to the proper angle to cause the grinding wheel to operate upon the interior of the cylinder 40 and be carried around a circular path by the slowly rotating shaft 23.

While either boring or grinding is being done, the screw 5 is simultaneously rotating the shaft 23 at a slow rate of speed and 45 gradually feeding the work to the tool, and in order that the speed of feed and the speed with which the tool is carried around its circular path may be synchronized, this drive is preferable. It is to be understood, 50 however, that separate mechanisms could well be employed for feeding the carriage 3 and rotating the shaft 23. In fact, said carriage could well be fed by hand, although in most cases the mechanical feed 55 will be used.

The belt 42 employed for rapidly driving shaft 29 when grinding the interior of the cylinder, may either be detachable as illustrated in the drawings, or a suitable mechanism such as a tight and loose pulley may 60 be employed for throwing said belt out of action when said shaft is to be locked against rotation by the nuts 41. Similarly,

although I have shown and described features of construction which will probably 65 operate to the best advantage, equivalents thereof can be used within the scope of the invention as claimed.

I claim:

1. In a machine of the class described, the 70 combination of a bed, a carriage movable along said bed, an auxiliary carriage shiftable transversely of said first named carriage and having on its upper side a rib extending transversely of said bed, a work 75 support adjustable along said auxiliary carriage and having in its lower side a notch receiving said rib, and means for holding said auxiliary carriage in adjusted position.

2. In a machine of the class described, the 80 combination of a bed, a carriage movable along said bed, an auxiliary carriage shiftable transversely of said first named carriage and having on its upper side a rib extending transversely of said bed, a pair of 85 work supporting brackets rising from said auxiliary carriage and adjustable along the same, said brackets having notches in their lower edges receiving said rib, means for locking said brackets and rib together, and 90 means for holding said auxiliary carriage in adjusted position.

3. A work holder of the class described comprising an elongated base plate having 95 in its lower side a longitudinal undercut groove to receive the transverse rib of a lathe carriage, the upper side of said plate having a longitudinal rib formed with a longitudinal undercut groove in its upper side, a work support notched in its base to 100 receive said rib, and a bolt for securing said support in place, said bolt being slidable in said groove of the rib.

4. In a machine of the class described, the 105 combination of a hollow shaft, means supporting said shaft for rotation but holding the same against longitudinal movement, means for slowly rotating said shaft, a bearing sleeve passing through said shaft and projecting beyond one end thereof, 110 means connecting said projecting end of said sleeve with the adjacent end of said hollow shaft for shifting said sleeve laterally, means pivotally connecting the other end of said sleeve to the corresponding end 115 of said shaft, a tool driving shaft passing rotatably through said sleeve, and means adjacent the pivoted end of said sleeve, for driving said tool carrying shaft.

In testimony whereof I have hereunto set 120 my hand in the presence of two subscribing witnesses.

FREDERICK A. BLACHLY.
